INVENTOR.
Robert H. Lindsay
BY

Hardway & Cather
ATTORNEY.S.

UNITED STATES PATENT OFFICE.

ROBERT H. LINDSAY, OF HOUSTON, TEXAS.

STILL.

Application filed December 16, 1921. Serial No. 522,848.

To all whom it may concern:

Be it known that I, ROBERT H. LINDSAY, citizen of the United States, residing at Houston, in the county of Harris and State of Texas, have invented certain new and useful Improvements in a Still, of which the following is a specification.

This invention relates to new and useful improvements in a still.

10 One object of the invention is to provide an apparatus of the character described which has been specially designed for the treatment of crude petroleum, whereby the lighter elements may be readily separated 15 from the heavier.

Another object of the invention is to provide an apparatus of this character whereby the residuum, remaining after the separation 20 of the lighter elements therefrom, will also be rendered lighter and easier handled and of greater utility.

With the above and other objects in view the invention has particular relation to certain novel features of construction, arrangement of parts and use an example of which is given in this specification and illustrated 25 in the accompanying drawings wherein:—

Figure 1 shows a side elevation of the apparatus, showing the furnace walls in section, and,

Figure 2 is an end view of the apparatus.

Referring now more particularly to the drawings, the numeral 1 designates an enclosing furnace, whose wall may be formed 35 of brick, concrete or other suitable material.

Above this furnace there is located a tank 2 which contains the oil to be treated. Leading from the bottom of this tank there is a down pipe 3 which is controlled by the gate valve 4 and whose lower end is connected into the T-section 5, by means of which it is connected to the pipes 6. These latter are arranged in zigzag turns 2 in vertical plane, within the furnace and at the 40 other end thereof they are connected into a tubular pipe 8 through which the residuum is discharged.

Above the furnace there is arranged the

outlet line 9 and the alternate coils are connected into this line through the tubes 10. 50

The oil to be treated circulates through the turns in the direction indicated by arrows in Figure 1, the lighter elements passing up through the tube 10 into the line 9, and the residuum passing off through the 55 pipe 8.

Underneath the turns are the pneumatic pressure lines 11, 11, which are connected to a suitable pressure line 12. The pressure lines 11 are provided with the upstanding nozzles 13 which are fitted through the stuffing boxes 14 of alternate sections of the turns 7 and above said nozzles these coil sections are restricted, as at 15.

The furnace is equipped with a suitable oil burner 16 which is supplied with fuel through the line 17 and which is connected to the air pressure line 12, through the tubular connection 18. The burner is arranged underneath the coils and heats them. 65

As the oil to be treated circulates through the coils it is broken up by the air jets from the nozzles 13 and the lighter elements are separated from the heavier and pass into the line 9 while the residuum is taken off 70 through the pipe 8 as above-stated. 75

What I claimed is:

A still including a furnace, a tank above the furnace, a pipe leading from the bottom of the tank, and formed into zig-zag turns lying in a vertical plane, within the furnace and terminating in a discharge outlet, an outlet line arranged above the furnace, a pneumatic pressure line beneath the turns of said pipe, upstanding nozzles connected into the pressure line, said nozzles extending into the lower ends of alternative turns of said pipe, and disposed to discharge pressure fluid into said turns with the current of fluid flowing through said pipe, said turns being restricted above the respective nozzles, tubes connecting the turns, which said nozzles enter, into said outlet line. 80 85 90

In testimony whereof I have signed my name.

ROBERT H. LINDSAY.
